UNITED STATES PATENT OFFICE.

OSCAR CARLOS WILLIAMS, OF WILLIAMSTOWN, WEST VIRGINIA.

HEATING-STOVE.

1,105,944.

Specification of Letters Patent.

Patented Aug. 4, 1914.

Application filed July 24, 1912. Serial No. 711,308.

To all whom it may concern:

Be it known that I, OSCAR C. WILLIAMS, a citizen of the United States, residing at Williamstown, in the county of Wood and State of West Virginia, have invented a new and useful Heating-Stove, of which the following is a specification:

This invention relates to heating stoves of that type utilizing gas as a fuel and in which the gas burners are located within a casing which is open in front and is provided with a deflector in the back thereof.

One of the objects of the invention is to provide improved means whereby air may be heated, said means including a novel arrangement of flues for conducting fresh air along the walls of the casing where it will be thoroughly heated before passing into the room.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

In the accompanying drawings the preferred form of the invention has been shown.

In said drawings:—Figure 1 is a front elevation of the heater. Fig. 2 is a central vertical section therethrough. Fig. 3 is a section on line A—B Fig. 2. Fig. 4 is a section on line C—D Fig. 2.

Referring to the figures by characters of reference 1 designates a casing of any suitable proportions and which is open in front, as shown at 2, there being a short wall 3 in front of the casing and extending upwardly from the bottom thereof, the upper edge of the wall merging into a transversely extending concaved deflector 4 which extends back to the rear wall of the casing. The deflector 4 has side walls 5 extending forward and spaced from the sides of the casing 1 so as to form air passages 6. A short front wall 7 extends downwardly from the top 8 of the casing and has an inwardly extending flange 9 along its lower edge. This flange is overhung by a flat angular flue 10 which extends upwardly and forwardly from the upper portion of the rear wall 11 of the casing and extends from one

side wall to the other of said casing, there being openings 12 in the side walls and through which air is free to pass from the flue 10. Another opening 13 is formed in the back wall 11 of the casing and communicates with the interior of the flue 10 and with the interior of a back flue 14 which is formed along the back face of the casing and extends from a point near the bottom of the casing upwardly to a point slightly above the opening 13. A pipe 15 extends from the back 11 of the casing and above the flue 10 and serves as an outlet for products of combustion. By providing the inclined flue 10, the wall 7, flange 9 and top 8, a tortuous passage is formed through which products of combustion will pass from the burner to the outlet pipe 15.

A burner G of any suitable construction is located in the casing close to and above the lower portion of the deflector 4. The products of combustion will rise within the casing and heat the walls 5 and the back 11 and will then pass over flange 9, between flue 10 and the front wall 7, and thence rearwardly over the flue to the outlet pipe 15. Air will rise within the flue 14 and pass through the opening 13 into flue 10 from which it will escape, by way of opening 12 into the room to be heated. At the same time a certain amount of heat will be radiated through the open front of the casing. The air contained within the spaces 6 will prevent the sides of the casing adjacent the burner from becoming overheated.

It will be apparent that by arranging flues as described, the air discharged into the room will be kept separate from the vitiated air and the products of combustion arising from the burner and, therefore, the heater can be used in a closed room without becoming objectionable.

What is claimed is:—

A heater including a casing open at its front, an inwardly directed horizontal flange extending throughout the width of the open front and along the upper edge of the opening, said flange constituting a deflector, an imperforate forwardly and upwardly inclined flat air conducting flue and deflector in the upper portion of the casing and opening at its ends through the sides of the casing, said flue being extended from the back wall of the casing and overhanging, at its front the deflecting flange, the front of said flue being spaced from the front wall of the

casing and there being an outlet in the back wall of the casing for combustion products, the said outlet being above the rear end of the conducting flue, and there being a space 5 between said conducting flue and the top of the casing for receiving products of combustion passing to the outlet, said space gradually increasing in cross sectional area toward the outlet, the said flue being extended continuously along the front, top and bottom thereof and having its upper and lower faces parallel, an air conducting flue upon the back of the casing and extending from a point above the bottom of the casing up to

and discharging into the flat air conducting flue, a rearwardly and upwardly curved deflector extending from the lower edge of the open front of the casing to the back wall of said casing, and a burner within the casing and close to and above said rearwardly and 20 upwardly curved deflector.

In testimony that I claim the foregoing as my own, I have hereto affixed my signature in the presence of two witnesses.

OSCAR CARLOS WILLIAMS.
